GOLF BAG STAND

Ernest M. Fritz, Chicago, Ill.

Application October 3, 1931. Serial No. 566,745

8 Claims. (Cl. 150—1.5)

My invention relates to golf bag stands, its purpose being to hold the golf bag in a slightly tilted position for enabling the golfer to choose his clubs at will and to put them in the bag or 5 take them out without bending over.

One of the objects of the invention is the provision of a foldable tripod one of the legs of which is provided with means for attachment to the golf bag.

10 Another of my objects is the provision of a tripod having adjustable features on one of the tripod legs whereby the golf bag stand may be secured to golf bags of various lengths or diameters.

15 Another of my objects is the provision of a golf bag stand in tripod form in which one of the legs of the tripod is in the form of a casing for receiving the other two legs when the tripod is folded, the casing having means for attachment 20 to a golf bag.

Another object which I have in view is the provision of a collapsible golf bag stand which may be opened or closed with a minimum of effort.

25 More specifically, I have as one of my objects the provision of an opening and closing device which is as nearly automatic in operation as possible, the opening being accomplished by merely releasing a spring which spreads the legs 30 and the closing being accomplished by merely moving a slide which retracts the legs and which at the same time tensions the spring.

Having in view these objects and others which 35 will be pointed out in the following description, I will now refer to the drawings, in which

Figure 1 is a view in perspective of my golf bag stand in operative position.

Figure 2 is a view in side elevation of a portion 40 of a golf bag with my golf bag stand secured thereto, the stand being in its inoperative position.

Figure 3 is a rear elevational view of the golf bag stand, the legs being retracted into the casing 45 of the stand.

Figure 4 is a view similar to Figure 3 but showing the rear wall of the casing of the stand cut away to disclose the interior parts of the casing and showing the legs in partly expanded position.

50 Figure 5 is a top plan view of the casing of the golf bag stand.

The golf bag stand includes a casing 10 having adjustable means for securing the casing to any and all golf bags regardless of their lengths and diameters. The casing 10 is semi-elliptical as

shown in the plan view of Figure 5, the side facing the golf bag being plane. The lower surface of the casing is inclined with respect to the vertical walls as shown at 11 in Figure 2, the inclination being such that the casing presents a 60 flat surface on the surface of the soil when the golf bag stand is in its operative position.

On the inner wall of the casing 10 and adjacent the lower extremity thereof is a metal strap 12 which is secured to the casing 10 by 65 means of a rivet 13. The rivet 13 is sufficiently loose to provide a pivotal connection between the casing 10 and the strap 12. The strap 12 is hinged at 14 to another strap 15 which in turn is rigidly secured to a piece of metal 16. 70 The piece of metal 16 is in arcuate form to conform to the shape of the bag to which it is secured by means of a thin and flexible metallic strap 17. The strap 17 is sufficiently flexible 75 to permit looping it over on itself to provide a buckle construction for securing the casing 10 to the golf bag. The flexible metallic strap 17 and its relation to the golf bag are similar at both ends of the golf bag and these will be more fully described when the top connections 80 are described. The construction at the base of the golf bag involving the connection of the casing 10 is such that a perfectly flexible or swivel joint is provided between the casing 10 and the golf bag to permit free play between the two 85 when the stand is being placed in its operative position.

At the upper extremity of the casing 10, the rear or inner wall is extended at 18 to some distance above the upper edge of the casing 10 and it is closed to form a guideway for the support 19, this support being secured to the upper edge of the golf bag by means to be subsequently described. The guideway 18 has considerable breadth as shown in Figure 2, the dimensions conforming to those of the support 19. A second guideway 20 is formed in the wall of the casing 10 by punching and forming the metal of that wall. 100

The support 19 is provided with two elongated vertical slots 21 in alignment with two apertures in the guideway 18. In the rear of the guideway 18 is a metallic plate 22, screws 23 or other suitable fastening devices passing through 105 the apertures of the guideway 18, through the slots 21 and into screw threaded apertures in the plate 22. The position of the support 19 with regard to the casing 10 may be thus adjusted by sliding the support 19 in the guideway 18. 110

and then tightening the screws 23. The purpose of this is to adjust the overall length of the slide 19 and the casing 10 to the length of the golf bag which is to be fitted with my stand.

5 Secured to the upper end portion of the slide 19 is another curved metallic plate 24 which is similar to the metallic plate 16 at the bottom of the casing. The plate 24 like the plate 16 is in arcuate form for seating against the cylindrical surface of the golf bag. Loops 25 are formed in the plate 24, these loops being designed to receive a strap 26. This strap may be made of any suitable material, my preferred construction being of very light flexible steel. The straps 17 and 26 are similar. The plate 24 is also provided with an ear 27 for engaging the strap 26 through an aperture in the strap for the purpose of securing the strap to the plate. In the case of both the bottom plate 16 and the top plate 24, the straps are carried around the golf bag and they are then carried through loops in the plates 16 and 24. The flexible bands 17 and 26 are both detachable at both of their ends from their supports.

25 The casing 10 is provided with an opening on its concave surface, this opening being normally closed by means of a closure 28. The closure 28 has top, bottom and intermediate fastenings so that it is possible to remove the closure in order to gain access to the interior of the casing when it becomes necessary to adjust or repair the interior construction. The lateral edges of the closure 28 are cut away so that when the closure is in position the casing 10 will be provided with two elongated vertical slots 29, the slots being designed for the passage of the legs and their braces into and out of the casing 10.

Inside the casing 10 there is a slide 30 having guideways 31 and 32, all of which are secured to the flat wall of the casing 10. The slide projects through the top well of the casing 10 and its upper end is outturned at 33 to provide a finger grip. It is obvious that the slide 30 may move up or down relative to the casing 10 and that it will be held in line by means of the guideways 31 and 32. The slide 30 is bent over at its lower extremity to form an abutment 30' which contacts with the lower guideway 32 to limit the upward movement of the slide 30. A coil spring 34 is secured at its upper extremity to the top wall of the casing 10 and it is secured at its lower extremity to a bracket on the slide 30. The obvious effect of the spring 34 will be to draw the slide 30 into its uppermost position. Two brackets 35 are rigidly secured to the flat wall of the casing 10 with their free arms slightly diverging. The legs 36 are kept at their upper ends with collars which terminate in loops 37, the loops 37 embracing the projecting portions of the brackets 35 to which they are pivotally connected. The brackets are so inclined that the pivotal movement of the legs 36 on the brackets will carry the legs freely through the slots 29 and into or out of the casing. Secured to the legs 36 are collars 38 having ears 39 to which brace links 40 are pivotally connected at their lower extremities between pairs of ears 41 which are rigidly secured to the slide 30. The effect of this construction is that the slide 30 will normally be drawn upward to its uppermost position carrying with it the brace links 40 which force the legs 36 outwardly. When the legs 36 are within the casing 10 they are engaged by clips 42 which normally tend to hold the legs 36 in their retracted position and which guide the

movement of the legs outwardly through the slots 29. The spring 34 will force the legs into their operative position but the retracted position of the legs may be restored by pushing down on the finger piece 33 until the legs engage the clips 42. When the slide 30 is pushed down the spring 34 is again tensioned.

As shown in Figures 4 and 5, a lever 43 is pivotally connected at 44 to the upper wall of the casing 10. This lever has movement through a limited arc through a slot in the casing 10. A projection 45 extends in the path of the lever 43, the projection being preferably made by stamping in the slide 30. When the legs 36 are in their retracted position the projection 45 will bear against the under side of the lever 43 to thus prevent upward movement of the slide 30. When the legs are in their operative position the projection 45, being integral with the slide 30, will be at a considerable distance above the lever 43. If then the lever 43 is swung on its pivot 44 out of engagement with the projection 45, the spring 34 will force the slide 30 upwardly and it will force the legs 36 into their operative positions. The device is also provided with a leaf spring 46 for normally urging the lever 43 into a position of engagement with the projection 45. In other words, when the lever 43 is moved out of its operative engaging position it will immediately be retracted to its original position under the action of the spring 46 when the pressure on the lever 43 is released. The projection 45 is so shaped that the slide 30 may be moved downwardly past the lever 43 so that the engagement of the projection 45 with the lever 43 will be automatic when the slide 30 is forced to its lowermost position by pressure on the finger piece 33.

From the foregoing description it will be obvious that the golf bag stand is one of extreme simplicity in operation. The golfer attaches it to his favorite golf bag which he carries to and from the golf course in the usual manner. When he has reached a position on the golf course he merely releases the trigger whereupon the spring forces the legs into operative position. The golf bag will then rest in an inclined position on the surface of the field, the inclination being the most convenient for giving access to the clubs. The golfer need not stoop over to reach any of the clubs which are all in the most convenient position accessible to the golfer. When the golfer moves from one spot to another on the course or when he returns from the course, he merely presses down with his thumb on the projection of the slide which simultaneously retracts the legs into the casing and tensions the spring so that the legs will be automatically restored to their operative position by a slight pressure on the trigger. The retraction of the legs into the casing is followed automatically by the action of the latch which prevents accidental expansion of the legs while the golf bag is being carried.

The attachment is light in weight so that it does not add any appreciable weight to the golf bag. It is so constructed that it may be attached to any golf bag regardless of its length or diameter. While the golf bag and the attachment are to be used mainly on the golf course, the attachment is so constructed that it can not injure the surface of a polished floor. The base of the casing and the feet of the legs are constructed of smooth metal without sharp edges or

corners so that they can not mar any surface with which they might come in contact.

Having thus described my invention in such full, clear, and exact terms that its construction and operation will be readily understood by others skilled in the art to which it pertains, what I claim as new and desire to secure by Letters Patent of the United States is:

1. A tripod stand for a golf bag including an elongated casing having means for attachment to the golf bag, a pair of legs secured within said casing for divergent movement relative to said casing and to each other, said casing being adapted to function as a third leg of said tripod support when said support is in operative position and as an enclosure for said pair of legs when said support is in its inoperative position. 10
2. A tripod attachment for golf bags, said attachment including a casing having a pair of legs pivotally secured to an inner wall thereof, said casing being provided with a pair of elongated slots for the passage of said legs into and out of said casing, a member secured within said casing to slide lengthwise thereof, and braces pivotally secured to said legs and to said slideable member. 20
3. A tripod attachment for golf bags, said attachment including a casing having a pair of legs pivotally secured to an inner wall thereof, said casing being provided with a pair of elongated slots for the passage of said legs into and out of said casing, a member secured within said casing to slide lengthwise thereof, braces pivotally secured to said legs and to said slideable member, and a spring for normally urging said slideable member into its uppermost position with said legs in their expanded or operative position. 30
4. A tripod attachment for golf bags, said attachment including a casing and a pair of legs pivotally secured to an inner wall thereof, said casing being provided with a pair of elongated slots for the passage of said legs into and out of said casing, a pair of clips within said casing for releasably engaging said legs when they are in their inoperative position and for guiding the movement of said legs into or out of the casing, a member secured within said casing to slide lengthwise thereof and having means for limiting the sliding movement thereof in both directions, and braces pivotally secured to said slideable member and to said legs. 40
5. A tripod attachment for golf bags, said attachment including a casing and a pair of legs pivotally secured to an inner wall thereof, said casing being provided with a pair of elongated parallel slots for the passage of said legs into and out of said casing, a member secured within said casing to slide lengthwise thereof, a tension spring secured to the upper wall of said casing and to said slideable member for normally urging said slideable member into its uppermost position, a pair of brace links secured to said legs and to said slideable member, means for limiting the upward movement of said slideable member, and an outturned projection at the upper extremity of said slideable member, the arrangement being such that downward pressure on said projection will simultaneously tension said spring and retract said legs into said casing. 50
6. A tripod attachment for golf bags, said attachment including a casing and a pair of legs pivotally secured to an inner wall thereof, said casing being provided with a pair of elongated parallel slots for the passage of said legs into and out of said casing, a member secured within said casing to slide lengthwise thereof, a tension spring secured to the upper wall of said casing and to said slideable member for normally urging said slideable member into its uppermost position, a pair of brace links secured to said legs and to said slideable member, means for limiting the upward movement of said slideable member, a latch for maintaining said slideable member in its lowermost position against the tension of said spring, a finger release for said latch, and an outturned projection at the upper extremity of said slideable member, the arrangement being such that downward pressure on said projection will simultaneously tension said spring and retract said legs into said casing. 60
7. A tripod attachment for golf bags, said attachment including a casing having a pair of legs pivotally secured to an inner wall thereof, means at the lower extremity of said casing for attachment to the golf bag, a support secured to the upper portion of said casing for slideable adjustment lengthwise thereof, means at the upper extremity of said support for attachment to the golf bag, said casing being provided with a pair of elongated slots for the passage of said legs into and out of said casing, and braces pivotally secured to said legs and slideably secured at their inner extremities to an inner wall of said casing. 70
8. A tripod attachment for golf bags, said attachment including a casing having a pair of legs pivotally secured to an inner wall thereof, means at the lower extremity of said casing for attachment to the golf bag, said means including a pair of pivotal connections, a support secured to the upper portion of said casing for slideable adjustment lengthwise thereof, means at the upper extremity of said support for attachment to the golf bag, said casing being provided with a pair of elongated slots for the passage of said legs into and out of said casing, and braces pivotally secured to said legs and slideably secured at their inner extremities to an inner wall of said casing. 80
